FOLDING TABLE HARDWARE

Roy F. McMahan, Louisville, Ky.

Application August 27, 1936, Serial No. 98,115

2 Claims. (Cl. 311—110)

My invention relates to a table equipped with mechanisms organized to provide a pivot and locking means for each individual supporting leg, whereby the latter can be folded to the closed position, or extended, in relation to the table top to the open position, and locked in either the open or closed position.

The primary object of the invention is to provide sturdy mechanisms of simple structure, not only for the legs of tables, known in the furniture industry as "folding" or card tables, but to simplify manufacture of the mechanisms and the tables.

A still further object of the invention contemplates an organization of metal and wood parts having superior enduring mechanical properties, the component parts of which can be readily produced expeditiously, assembled and finished to constitute the final product.

With the foregoing and other objects, which will be revealed as the description of the details of the construction proceeds and hereinafter claimed, it must be understood that changes from the selected embodiment of my invention can be indulged without departing from the scope of my invention.

Drawing

Figure 1 is a perspective view of the corner section of a folding table inverted to show the leg supporting mechanism, and the upper portion of a table leg in open or erected position; Fig. 2 is a similar view, enlarged and showing the leg in the closed or folded position; Fig. 3 is a horizontal sectional view taken along line 3—3 of Fig. 1; Fig. 4 is an enlarged sectional view taken along line 4—4 of Fig. 3; and Fig. 5 is a partial plan view of one face of the U shaped ferrule that is attached to leg 10.

Structure

Numerical 10 indicates the top portion of a wooden table leg, which is embraced by a U shaped ferrule 11 that is anchored to the leg by crimping, or rolling, the free ends of the ferrule into the table leg, in accordance with the teachings of my copending application, Ser. No. 70,933, filed in Division 14, March 26, 1936.

An L shaped sheet metal bracket, generally represented by 12, consists of legs 13 and 14. From each of these legs are lanced and formed 90° angled tongues 15. There is also an arm 141, lanced from leg 14, which is substantially 90° to leg 14 and parallel to leg 13. Both arm 141 and leg 13 are perforated to receive a shaft 16, which

forms the bearing for leg 10 by extending through similar and registering perforations in ferrule 11, and necessarily through a hole in the leg. Obviously, this hole can be a bearing surface, or can be of a diameter sufficient to provide clearance, as the metal parts can be organized to suffice for the bearing. Holes 18 in leg 13 are axially disposed to holes 20, 21 in ferrule 11, and receive a spring pressed locking pin 22; one hole 18 being employed for the erected or open position, note Fig. 3, and another hole 18 for the closed position, note Fig. 1.

Numerical 25 designates a table top, which is reinforced by perimetric rails 26. The inside face of each rail is fashioned with a groove or slot 27, 15 preferably in uniform relation, so that when the flange is assembled to the top, all the grooves will fall in the same plane. The proportions, disposition and inter-relation of tongues 15 and grooves 27, are so organized that when the assembly is completed and secured to the rails by screws 19, as shown by the accompanying drawing, there results a very rigid and positive folding table mechanism that provides a definite alignment for the leg and a material reinforcement of the table rails; thereby contributing to the stability of the complete table.

A locking pin 22 is fashioned with a head 221, diametrical lugs 29, and a tapered end to provide a compensating means when irregularities 30 and wear are encountered. To permit assembly of the ferrule and the plunger, as shown in Fig. 3, hole 21 has been notched as shown in Fig. 5 to admit lugs 29.

Open coiled helical spring 22 is threaded onto the plunger as the plunger is inserted. This leaves the spring disposed between the lugs and the tapered end of the plunger. To transfer the spring to the position shown in Fig. 3, the plunger is rotated, and the spring temporarily secured, as with pliers, whereupon the lugs first spread the end of the outside coil, and then each coil serially until the spring is lodged as shown.

Operating lever 30 is fulcrumed to the ferrule at 31 by a free rivet, and is provided with an elongated hole, which embraces plunger 22 adjacent head 221. This hole is sufficiently large to pass lugs 29.

Further details of the lock structure, its merits 50 and operation are not believed important as same forms no part of this invention. During the fabrication of leg 10 a recess 32 is formed in leg 10, so as to permit free movement of the locking pin 22 and spring 28. It will be understood that the 55

assembly of the locking pin and associated parts with the ferrule is completed before it is crimped or secured to leg 18.

5

Operation

Pressure on the free end of lever 30, which is at all times accessible, frees the tapered end of pin 22 from a hole 18 and thereby unlocks the leg, thus permitting free movement of the latter to 10 open or folded position. Thus the table leg can be manipulated by one hand.

Having thus described my invention, I claim:

1. In a table, angularly connected side rails having aligned horizontal cuts extending longitudinally of and laterally into the inner faces thereof and adjacent the corners formed by the connected side rails, a leg supporting bracket disposed in said corners and having mounting arms overlying said cuts and secured to and in contact with the inner faces of said rails, and rigid tongues extending laterally from said arms and lodged in said cuts, whereby said bracket is

aligned with said rails and said rails are reinforced at said corners.

2. In a table, angularly connected side rails having aligned horizontal cuts extending longitudinally of and laterally into the inner faces 5 thereof and adjacent the corner formed by the connected side rails, a leg supporting bracket disposed in the said corner and having angularly connected mounting arms overlying said cuts and secured to and in contact with the inner face of 10 the corresponding rails, a rigid tongue extending laterally from each arm substantially adjacent the outer end thereof and lodged in the cut of the corresponding rail, and another rigid tongue extending laterally from one arm of said bracket 15 substantially adjacent the corner formed by the connected arms and lodged in the cut of the corresponding rail, whereby said bracket is aligned with said rails and the rails are re-inforced at the said corners.

ROY F. McMAHAN.
